COMBINED MEASURING SPOON AND WEIGHING TRAY FOR DIET FOOD PORTIONS

William Macowski, Jr., Caldwell, N.J., assignor to
Ketcham & McDougall, Inc., Roseland, N.J.

Filed Aug. 24, 1970, Ser. No. 24,673

Term of patent 14 years

Int. Cl. D7—99

U.S. Cl. D44—10

FIG. 1

FIG. 2

FIG. 3

FIG. 4

FIG. 1 is a perspective view of a combined measuring spoon and weighing tray for diet food portions, embodying my new design;

FIG. 2 is a top plan view;

FIG. 3 is a front elevational view; and

FIG. 4 is a bottom plan view.

I claim:

The ornamental design for a combined measuring spoon and weighing tray for diet food portions, as shown.
